UNITED STATES PATENT OFFICE

GUY C. DAVIS, OF ROCKFORD, ILLINOIS, AND DONALD G. GRISWOLD, OF LOS ANGELES, CALIFORNIA, ASSIGNORS OF FORTY PER CENT TO SAID GUY C. DAVIS, OF ROCKFORD, ILLINOIS, AND SIXTY PER CENT TO HAROLD L. OFFENHISER, OF PEARL CITY, ILLINOIS

FOLDING TABLE AND BENCH

Application filed February 28, 1929. Serial No. 343,313.

This invention relates to folding furniture generally, but is more particularly concerned with an improved folding table and bench to form a luncheon set suitable for camping or outing use, although adapted likewise for use in the home or in lunch rooms or other places wherever a compact, strong portable folding outfit of this kind may be desired.

The principal object of our invention is to provide a table and bench which can be quickly and easily set up ready for use and just as easily folded to be set aside or stored away and which, when unfolded for use, is extremely strong and rigid to give good service, and is arranged to fold to an extremely compact size such that the table and bench, or two benches as the case may be, will take up very little room. For example, the set when packed, may be clamped flat on the running board of an automobile or may be clamped on the running board in such a position that it will serve the purpose of a luggage carrier.

Among the features of our invention may be enumerated the following:

(1) The provision of a folding table and bench or benches wherein the table top is formed by two leaves hinged together to fold onto one another or to be disposed side by side, each of the two leaves of the table top being preferably of the same size as the top for the bench or benches so that when the outfit is folded and packed, it makes a compact and symmetrical bundle easy to handle.

(2) The provision of the table and bench or benches having the tops thereof grooved longitudinally on the underside thereof for reception of the folding legs and struts therefor whereby to enable the folding of the table to the smallest possible size, namely, that of a half of the table top itself and likewise, the folding of the bench to the smallest possible size, namely, that of the top thereof.

(3) The provision of a table, the top of which is formed, as stated above, by the unfolding of two leaves hinged together, and having criss-crossed legs at opposite ends thereof with struts extending from the underside of the table top to the

intersections of the criss-crossed legs to make for rigidity, the strut for one end extending from the one leaf adjacent the hinges connecting the two leaves to the intersection of the one pair of legs and the other strut extending from the other leaf adjacent the hinge connections between the leaves to the intersection of the other pair of legs whereby to avoid having too much of the load borne by the hinges themselves and also prevent the top from sagging or buckling at the middle thereof.

(4) The provision of a table and bench or benches, the folding legs and reinforcing struts of which are joined to the top pieces by universal joint connections affording the desired range of movement for the legs and struts with reference to the top pieces to enable the criss-crossing of the legs and the coupling and uncoupling of the legs and struts, the said universal joints being of extremely small size, yet made in such a way as to afford the requisite strength.

(5) The provision in connection with the coupling of each pair of criss-crossed legs with its strut of a latch arranged to be slid into and out of locking position engaging beneath the head of a stud pivotally mounted on the end of the strut and entered through registering holes in the criss-crossed legs, the said latch being formed on the outside face thereof to make wedging engagement with the head of the stud and thus minimize any danger of the connection working loose and permitting collapse of the table or bench.

The invention is illustrated in the accompanying drawings, wherein—

Figure 1 is a perspective view showing the table almost completely folded, the completely folded condition being represented in dotted lines;

Fig. 2 is a similar view of one of the benches;

Fig. 3 is a perspective view of the folded table and bench slipped into a carrying case for transportation or storage;

Fig. 4 is a side view of the table set up for use;

Fig. 5 is an end view of the table and bench;

Fig. 6 is an elevational view of one of the universal joint connections provided for 5 the legs and struts;

Fig. 7 is a longitudinal section through Fig. 6 on the line 7—7 thereof, this view also corresponding to a section taken, say, on the line 7—7 of Fig. 1;

10 Fig. 8 is an elevational view of a connection between two criss-crossed legs and the strut cooperating therewith, this view serving to show the latch provided on one of the legs in locking engagement with the 15 head of the stud on the strut;

Fig. 9 is a vertical section through Fig. 8 on the line 9—9 thereof, and

20 Fig. 10 is a view of the free end of one of the struts showing the stud pivotally mounted thereon.

The same or similar reference numerals are applied to corresponding parts throughout the views.

The table top 10 is made up of two boards 25 A and B hinged together on their underside, as indicated at 11, so as to fold onto one another, as indicated in dotted lines in Fig. 1, and unfold into position alongside one another, as shown in full lines in Figs. 30 1 and 5. The bench top 12, or rather, each bench top, inasmuch as two benches may be provided in connection with one table, is made from a single board C. The boards A and B are of equal size and of the same 35 size as the board C so that they are all arranged to fit neatly in a carrying case 13, shown in Fig. 3, made of canvas or other suitable waterproof material and having a flap 14 for closing one end thereof provided 40 with snap fasteners 15, and having the handle 16 at a mid point thereon for the carrying thereof. The fact that the boards are of the same size makes the bundle of a symmetrical form, easier to handle, and 45 easier to clamp onto the running board of the automobile, if that is desired. The legs and struts for the table and bench are all arranged to fold into grooves provided for the reception thereof on the undersides of 50 the boards A, B and C, as will presently appear, so that the maximum possible compactness is arrived at; the table reduces to the size of the two superposed boards A and B forming the top 10, and the bench reduces 55 to the size of the board C forming the top 12 thereof. This and other features of construction embodied in the improved table and bench of our invention is fully described hereinafter.

60 The bench and table are of substantially the same construction, the only difference being that the table has the top 10 made of two leaves hinged together as described above. A description of the table will, 65 therefore, serve largely as a description of

the bench, too. At the outset it will be noted that the table has a pair of legs 17 and 18 at one end thereof fastened by means of universal joints 19 to the underside of the boards A and B permitting the legs to 70 be criss-crossed, as shown in Fig. 5. A strut 20, also fastened by means of a universal joint 19, has a stud 21 pivotally mounted on the free end thereof by means of which the same is arranged to be coupled with the 75 criss-crossed legs 17 and 18 at the point of intersection, as will presently appear. Similarly, the other end of the table has a pair of legs 22 and 23 fastened to the boards A and B respectively by joints 19 and, cooperating with these legs, a strut 24 fastened by means of a joint 19 and equipped with a stud 21 on the free end thereof to couple the strut with the criss-crossed legs 22 and 23 at the point of their intersection. The legs 80 17, 18, 22 and 23, together with their joints 19, are all arranged to fit snugly in longitudinal grooves 25 cut in the underside of the boards A and B, these grooves extending for 85 a good part of the length of the table, as shown, to accommodate the full length of each leg so as not to leave any part projecting. Similarly, the struts 20 and 24, together with their joint 19, are arranged to fit snugly in shorter grooves 26 provided 90 therefor in the boards A and B. So much for a general description of the type of construction employed. Before proceeding to a detailed description of the various structural features, it will be observed that the 95 bench has a similar complement of legs 17', 18', 22' and 23' and struts 20' ad 24', the legs and struts being all fastened by means of universal joints 19 and the struts being equipped with studs 21 on the free ends 100 thereof, and the legs being arranged to fit in grooves 25 and the struts in a groove 26 provided in the underside of the board C. Obviously, the criss-crossed legs, coupled with the struts, afford a very rigid support for 105 the top 10 of the table or the top 12 of the bench. In the case of the bench where the top is in one piece, there is, of course, no difficulty in obtaining the desired rigidity, but in the case of the table, the fact that the 110 top is formed by two leaves hingedly joined together necessitates proper disposition of the struts to avoid having too much of the load being borne by the hinges 11, as well as to prevent sagging or buckling of the 115 table top at the middle and, in that case, it will be observed that we have fastened one strut 20 onto the board A on one side of the hinge connection between the boards A and B, and have fastened the other strut 24 onto the board B on the other side of the hinge connection. Thus the strut 20 assumes the load imposed on the board A at the middle of the table top which would otherwise be transmitted to the hinges 11, and the strut 120 125 130

24 assumes the load imposed on the board B at the middle of the table top which would otherwise be borne by the hinges. It is found that with this arrangement of the 5 struts, the table top is kept quite rigid and will not tend to sag or buckle at the middle thereof.

The legs and struts for the table and bench, or benches, are all preferably made 10 from channel iron strips cut to the proper lengths, this material affording the desired rigidity and strength even though strips of relatively small cross-section and proportionate light weight are used, and, of course, 15 that is of great importance in a portable outfit of this kind where compactness and light weight are especially desired. The free ends of the legs are cut off diagonally, as shown at 27, to afford good footing. 20 This kind of material also lends itself particularly well to the connection of the legs and struts with the boards A, B and C by means of the universal joints 19, and also makes it a simple proposition to pivotally 25 mount the studs 21 on the free ends of the struts 20, the parallel flanges of the channels being taken advantage of in both cases, as will now be described.

Considering first the connections between 30 the legs or struts and the universal joints 19, it will be apparent that a description of one of these connections will suffice for all. Refer to Fig. 6. In this figure it will be observed that the universal joint 19 comprises a strap 28 fastened as by means of screws 29 in a recess 30 adjacent the end of the groove 26 wherein the strut 20 is received, the strap 28 having the one end thereof bent at right angles, as shown at 31, to project into the end of the groove 26. A U-shaped connector or intermediate member 32, which is preferably formed between dies from a piece of sheet metal, has the parallel arms thereof fitting between extensions 33 of 45 the flanges of the channel strip from which the strut 20 is formed, and is pivotally connected thereto by means of a pin 34 passed through registering holes in the two parts referred to. The projecting ends of the 50 pin 34 are upset, as indicated at 35, to make a permanent connection. The extensions 33 are formed by simply cutting away a part of the web of the channel at the end of the strip, as indicated at 36. The connector 32 55 is pivotally mounted on the inturned end 31 of the strap 28 by means of a rivet pin 37, the latter affording pivotal movement for the connector 32 about an axis at right angles to the pin 34. Thus the struts, or the 60 legs, for that matter, are free to swing about a horizontal axis, due to the pin 34, to a position at right angles to the table top or bench top as the case may be, as indicated in dotted lines in Fig. 7, or to a position 65 making an acute angle with the top. Fur-

thermore, each strut or leg has freedom for swinging movement laterally, due to the pin 37, so that the legs for the table, or bench, as the case may be, can be disposed criss-crossed, and the struts 20 and 24 for the table can be swung sidewise sufficient to make connection at their free ends with the criss-crossed legs at the point of intersection of the latter. Needless to say, the universal joint just described is of extremely 70 small size but is still nevertheless of ample strength. The fact that the parts 28 and 32 can be formed from sheet metal between dies and these parts can be fastened together by rivet pins, cuts the cost down to a minimum. 75

The studs 21 have connector yokes 38, similar in form to the connectors 32, by means of which the same are pivotally mounted on the free ends of the struts 20, 24, 20' and 24' (see Figs. 9 and 10). The connector 38 is substantially U-shaped and formed from sheet metal between dies like the connector 32. The parallel arms thereof fit between extensions 39 of the flanges 80 of the channel strip from which the strut is formed, the extensions being provided by simply cutting away a portion of the web at the end of the strip, as shown at 40. A rivet pin 41, passed through registering 85 holes in the two parts, serves to permanently join the same. The stud 21, which is annularly grooved at the outer end thereof, as shown at 42, to provide a flat head 43, has the inner end thereof reduced, as shown at 44, for extension through a hole in the connector 38 to permit the fastening of the stud 21 to the connector by upsetting of the reduced end of the stud, as shown at 45. Obviously, this construction makes for strength 90 and economy as well. The stud 21, by reason of its pivotal mounting on the end of the strut, can be passed through registering holes 46 in the webs of the channel strips from which the legs of the table or bench are formed, as shown in Fig. 9. The stud 21 is long enough to have the head 43 thereon project appreciably when the stud is entered through the criss-crossed legs. This 95 permits locking the coupled parts together by means of a latch 47 cooperating with the head 43 of the stud. The latch 47 is formed from a piece of sheet metal having one end thereof curled slightly to provide a finger hold 48, by means of which the latch may be slid into and out of locking position. A rivet pin 49, entered through a slot 50 in the latch 47, provides a permanent mounting for the latch 47 on one of the criss-crossed legs, and at the same time serves as a guide for the latch in the sliding thereof to and fro. A slot 51 is punched in the end of the latch 47, permitting the latch to straddle the projecting end of the stud 21 in the 100 groove 42 thereof. The end of the latch is 105

110

115

120

125

130

preferably slightly tapered, as indicated at 52, so that the outside face of the latch will make wedging engagement under the head 43 as the latch is forced home. Thus there is no likelihood of the coupled parts working loose and possibly permit collapse of the table or bench. There is enough leeway afforded by the taper on the end of the latch to insure a tight connection even though the 10 cooperating parts may become slightly worn.

It should be evident from the foregoing that the table and bench can be removed from the carrying case and set up ready for use in a couple of minutes, and that it is an 15 extremely simple matter for any mechanically unskilled person to handle the same. Furthermore, there are no loose parts that are apt to be lost or mislaid, which, of course, is a decided advantage. The economical construction of the outfit makes it a 20 sound investment despite the fact that most people will only get occasional use out of it. The lightness and compactness of the outfit is of advantage not only from the 25 standpoint of the user but likewise from the standpoint of the manufacturer, for it permits shipment of the outfit by parcel post.

It is believed the foregoing description conveys a clear understanding of the various 30 objects and advantages of our invention. While the specification has been confined to a folding table and bench, it should be understood that those are only two embodiments of our invention and that various 35 other articles of furniture may be made employing substantially the same construction, as for example miniature tables and benches for children's use, foot stools, radio benches, sewing tables, card tables, banquet tables, 40 and other articles of a generally similar description. It is also contemplated to make ironing boards, wall-paper hanger's tables and the like, using the same construction. The appended claims should, therefore, be 45 construed as applying to folding furniture generally.

We claim:

1. An article of folding furniture, such as a table or bench, comprising a top, a pair 50 of legs at each end thereof each having a universal joint connection with the underside of the top so as to permit folding of the legs alongside the top and unfolding as well as criss-crossing thereof, there being 55 narrow grooves provided in the underside of the top extending from the said universal joint connections and adapted to neatly receive the legs when each is folded, a strut for each end of said top having a 60 pivotal connection with the underside thereof so as to permit folding thereof alongside the top and unfolding to an operative position extending toward the intersection of the criss-crossed legs, there being a narrow 65 groove provided therefor in the underside

of the top extending from said pivotal connection so as to neatly receive the same when folded, and means for fastening the free end of the struts with the criss-crossed legs at the points of intersection. 70

2. An article of folding furniture, such as a table or bench, comprising a top, a pair of legs at each end thereof each having a universal joint connection with the underside of the top so as to permit folding of each of the legs separately alongside the top and unfolding as well as criss-crossing thereof, a strut for each end of said top having a pivotal connection with the underside thereof so as to permit folding thereof alongside the top and unfolding to an operative position extending toward the intersection of the criss-crossed legs, each pair of legs having holes provided therein arranged to be brought into register at the points of intersection when the legs are criss-crossed, and studs pivotally mounted on the free ends of the struts and arranged to be extended through the registering holes whereby to fasten the struts to the criss-crossed legs at the points of intersection of the latter. 75

3. A structure as set forth in claim 2 wherein each strut is formed from a strip of channel shaped cross-section, and wherein the pivotal mounting of the stud on the free end of said strut comprises a substantially U-shaped connector having the parallel arms thereof extending alongside the parallel flanges of the channel member and pivotally connected therewith, said connector member having the stud mounted thereon between the parallel arms thereof and projecting therefrom in the opposite direction from the arms. 80

4. An article of folding furniture, such as a table or bench, comprising a top, a pair of legs at each end thereof having universal joint connections with the underside of the top so as to permit folding of the legs alongside the top and unfolding as well as criss-crossing thereof, a strut for each end of said top having a pivotal connection with the underside thereof so as to permit folding thereof alongside the top and unfolding to an operative position extending toward the intersection of the criss-crossed legs, each pair of legs having holes provided therein arranged to be brought into register at the point of intersection when the legs are criss-crossed, studs pivotally mounted on the free ends of the struts and arranged to be extended through the registering holes whereby to fasten the struts to the criss-crossed legs at the points of intersection of the latter, the free end of each stud being arranged to project slightly when the studs are entered through the registering holes in the criss-crossed legs, and a locking part for each pair of legs ar- 85 90 95 100 105 110 115 120 125 130

ranged to cooperate with the projecting end of the stud.

5. An article of folding furniture, such as a table, comprising a top formed of two leaves hinged together to fold onto one another or unfold alongside one another, a pair of legs for each end of said top, one leg of each pair being mounted on one leaf and the other on the other leaf, the legs having universal joint connections with the underside of the top to permit folding the same alongside the top and unfolding as well as criss-crossing thereof, a pair of struts, one for each pair of criss-crossed legs, the one having pivotal connection with one leaf adjacent the hinges joining the leaves and the other having pivotal connection with the other leaf adjacent the hinges substantially as and for the purposes described, the struts being thereby arranged to fold alongside the top and unfold to operative positions extending toward the points of intersection of the pairs of criss-crossed legs, and means for fastening the free ends of said struts to the criss-crossed legs at the points of intersection of the latter.

6. An article of folding furniture, such as a table, comprising a top formed of two leaves hinged together to fold onto one another or unfold alongside one another, a pair of legs for each end of said top, one leg of each pair being mounted on one leaf and the other on the other leaf, the legs having universal joint connections with the underside of the top to permit folding the same alongside the top and unfolding as well as criss-crossing thereof, a pair of struts, one for each pair of criss-crossed legs, the one having pivotal connection with one leaf adjacent the hinges joining the leaves and the other having pivotal connection with the other leaf adjacent the hinges substantially as and for the purposes described, the struts being thereby arranged to fold alongside the top and unfold to operative positions extending toward the points of intersection of the pairs of criss-crossed legs, each pair of criss-crossed legs having holes provided therein arranged to register at the point of intersection when the legs are criss-crossed, and a stud pivotally mounted on the free end of each of said struts and arranged to be entered through the registering holes whereby to fasten the struts to the criss-crossed legs.

60 7. An article of folding furniture, such as a table, comprising a top formed of two leaves hinged together to fold onto one another or unfold alongside one another, a pair of legs for each end of said top, one leg of each pair being mounted on one leaf and the other on the other leaf, the legs having universal joint connections with the underside of the top to permit folding the same alongside the top and unfolding as well as

criss-crossing thereof, a pair of struts, one for each pair of criss-crossed legs, the one having pivotal connection with one leaf adjacent the hinges joining the leaves and the other having pivotal connection with the other leaf adjacent the hinges substantially as and for the purposes described, the struts being thereby arranged to fold alongside the top and unfold to operative positions extending toward the points of intersection of the pairs of criss-crossed legs, each pair of criss-crossed legs having holes provided therein arranged to register at the point of intersection when the legs are criss-crossed, a stud pivotally mounted on the free end of each strut and arranged to be extended through the registering holes in the criss-crossed legs, the outer ends of said studs being annularly grooved to provide heads on the outer ends thereof, the headed end of each stud being arranged to project slightly when the studs are entered through the registering holes, and a locking latch slidably mounted on one leg of each pair having a slotted end arranged to enter beneath the heads of the studs.

8. A structure as set forth in claim 7 wherein each latch is provided with a tapered face adjacent the slot in the end thereof arranged to make wedging engagement with the underside of the head of the stud substantially as and for the purpose described. 95

9. In an article of folding furniture, such as a table or bench, a body member, a leg or other member arranged to be connected therewith for universal pivotal movement, said last mentioned member being formed from a strip of channel shaped cross-section, and a universal joint for pivotally connecting the end of said channel member with the body member, comprising a strap fastened to the body member and having one end thereof bent at right angles, a substantially U-shaped connector pivotally mounted on the bent end of the strap for movement about a certain axis, the parallel arms of said connector extending alongside the parallel flanges of the channel member, and means pivotally connecting the arms with the flanges to permit swinging movement of the channel member relative to the connector about an axis at right angles to the other axis referred to, and, hence, universal movement of the channel member relative to the body member.

10. In an article of folding furniture, such as a table or bench, the combination of a body member, a leg or other member arranged to be mounted thereon for universal swinging movement relative thereto, said body member having a groove provided therein for reception of the other member in folded position, the latter member being formed from a strip of channel shaped cross- 130 125

- section, and a universal joint providing a mounting for the end of said channel member in one end of said groove comprising a strap fastened to the body member and 5 having one end thereof bent at right angles and projecting into the end of the groove, a substantially U-shaped connector pivotally mounted on the bent end of said strap in the end of said groove for movement relative to the strap about a certain axis, the parallel arms of said connector extending alongside the parallel flanges of the channel member, and means pivotally connecting the arms with the flanges to permit swinging movement of the 70 channel member relative to the connector about an axis at right angles to the other axis referred to, and, hence, universal movement of the channel member relative to the body member.
- 10 11. An article of folding furniture, such as a table, comprising a top formed of two leaves hinged together to fold onto one another or unfold alongside one another, a pair of legs for each end of said top, one leg 15 of each pair being mounted on one leaf and the other on the other leaf, the legs having universal joint connections with the underside of the top to permit folding the same alongside the top and unfolding as well as 20 criss-crossing thereof, there being narrow grooves provided in the underside of the top extending from the said universal joint connections and adapted to neatly receive the legs when each is folded, a pair of struts, 25 one for each pair of criss-crossed legs, the one having pivotal connection with one leaf adjacent the hinges joining the leaves and the other having pivotal connection with the other leaf adjacent the hinges substantially 30 as and for the purposes described, the struts being thereby arranged to fold alongside the top and unfold to operative positions extending toward the points of intersection of the pairs of criss-crossed legs, there being a narrow groove provided in each leaf extending 35 from the pivotal connection of the strut therewith adapted to neatly receive the strut when folded, the one leaf being thereby adapted for folding directly onto the other 40 when the legs and struts are folded into the grooves, and means for fastening the free ends of said struts to the criss-crossed legs at the points of intersection of the latter.
- 45 12. In an article of folding furniture, such as a table or bench, a body member, a leg or other member arranged to be connected therewith for universal pivotal movement, said last mentioned member being formed from a strip of channel-shaped cross-section, 50 and a universal joint for pivotally connecting the end of said channel member with the body member comprising a supporting element on the body member, a substantially U-shaped connector pivotally mounted on 55 the supporting element for movement about

a certain axis, the parallel arms of said connector extending alongside the parallel flanges of the channel member, and means pivotally connecting the arms with the flanges to permit swinging movement of the 70 channel member relative to the connector about an axis at right angles to the other axis referred to, and, hence, universal movement of the channel member relative to the body member.

75 13. In an article of folding furniture, such as a table or bench, a body member, a leg or other member arranged to be connected therewith for universal pivotal movement, said last mentioned member being formed from a strip of channel-shaped cross-section, 80 and a universal joint for pivotally connecting the end of said channel member with the body member comprising a supporting element on the body member, a substantially U-shaped connector pivotally mounted on the supporting element for movement about a certain axis, the parallel arms of said connector extending between the parallel flanges of the channel member, and means pivotally connecting the arms with the flanges to permit swinging movement of the channel member relative to the connector about an axis at right angles to the other axis referred to, and, hence, universal movement of the channel member relative to the body member.

85 14. In an article of folding furniture, such as a table or bench, a body member, a leg or other member arranged to be connected therewith for pivotal movement, said last mentioned member being formed from a strip of channel-shaped cross-section, 90 and a joint for pivotally connecting the end of said channel member with the body member comprising a supporting element on the body member, a substantially U-shaped connector pivotally mounted on the supporting element for movement about a certain axis, the parallel arms of said connector extending alongside the parallel flanges of the channel member, and means pivotally connecting the arms with the flanges to permit swinging movement of the channel member relative to the connector about an axis at right angles to the other axis referred to, and, hence, universal movement of the channel member relative to the body member, the web of the channel member being cut away at the connection with the U-shaped connector to permit a wide range of movement of the channel member relative to the connector.

95 15. In an article of folding furniture, such as a table or bench, a body member, a leg or other member arranged to be connected therewith for pivotal movement, said last mentioned member being formed from a strip of channel-shaped cross-section, 100 and a joint for pivotally connecting the end of said channel member with the body member comprising a supporting element on the body member, a substantially U-shaped connector mounted on and extending from said supporting element with the parallel arms thereof extending alongside the parallel flanges of the channel member, and means pivotally connecting the arms with the flanges to permit swinging movement of the channel member relative to the connector.

105 110 115 120 125 130

110 115 120 125 130

115 120 125 130

thereof extending between the parallel flanges of the channel member, and means pivotally connecting the arms with the flanges to permit swinging movement of the channel member relative to the connector, the web of said channel member being cut away at said connection whereby to allow for a wide range of movement of the channel member relative to the connector.

10 16. In an article of folding furniture, the combination with a body, of a leg or other member pivotally mounted thereon for swinging movement to and from folded position, a strut or other member also pivotally mounted on the body member for swinging movement to and from folded position, at least the latter member being of channel-shaped cross-section for the desired strength and rigidity as well as lightness, a U-shaped connector having the parallel arms thereof extending alongside the parallel flanges of the last mentioned channel member at the free end thereof, means pivotally connecting the arms with the flanges to permit swinging movement of the connector relative to the channel member, there being an opening provided in the first mentioned member, and a stud carried on the cross-portion of the U-shaped connector and extending therefrom and arranged to be entered through the last mentioned opening for connecting the members together.

In witness whereof we have hereunto affixed our signatures.
